CLAIM

The ornamental design for a dispenser, as shown and described.

DESCRIPTION

FIG. 1 is a perspective view of a top, front, and left side of an ornamental design for a dispenser;

FIG. 2 is a front elevational view of the dispenser of FIG. 1, the rear elevational view being a mirror image thereof;

FIG. 3 is a left side elevational view of the dispenser of FIG. 1, the right side elevational view being a mirror image thereof; FIG. 4 is a top plan view of the dispenser of FIG. 1; and, FIG. 5 is a bottom plan view of the dispenser of FIG. 1.

The dash-dash-dash broken lines are for the purpose of illustrating environmental structure and form no part of the claimed design. The shade depicted in FIGS. 1-5 may comprise a porous or non-porous material and may be transparent, translucent or opaque.
